UNITED STATES PATENT OFFICE.

HARRY J. ROBINSON, OF BOSTON, MASSACHUSETTS, ASSIGNOR TO THE MOSLER SAFE COMPANY, OF HAMILTON, OHIO, A CORPORATION OF NEW YORK.

DESIGN FOR A NIGHT SAFE DEPOSITORY.

Application filed May 25, 1928. Serial No. 26,862. Term of patent 14 years

To all whom it may concern:

Be it known that I, HARRY J. ROBINSON, a citizen of the United States, residing in the city of Boston, county of Suffolk, and State of Massachusetts, have invented a new, original, and ornamental Design for Night Safe Depository, of which the following is a specification, reference being had to the accompanying drawing, forming a part hereof.

I claim:

The ornamental design for a night safe depository, as shown.

HARRY J. ROBINSON.
